United States Patent Office.

NELSON JOHNSON, OF JASPER, NEW YORK.

Letters Patent No. 73,338, dated January 14, 1868.

IMPROVEMENT IN SWAGES FOR SAW-TEETH.

The Schedule referred to in these Letters Patent and making part of the same.

TO ALL WHOM IT MAY CONCERN:

Be it known that I, NELSON JOHNSON, of Jasper, in the county of Steuben, and State of New York, have invented a new and useful Swage for Saw-Teeth; and I do hereby declare the following to be a full, clear, and exact description of the same, reference being had to the accompanying drawings, which are made a part of this specification.

This invention relates to setting or spreading the ends of saw-teeth, and consists, first, in the provision, on the swage-stock, of notches or teeth, which operate in conjunction with similar notches or serrations on the shank of the saw-tooth, to hold the latter to the swage-stock and prevent it from being driven off of the supporting-die by the action of the hammer upon the stamping, striking-die; second, in the provision of means for adjusting the supporting-die, or equivalent means for adjusting the bearing-point of the saw-tooth on the swage-stock, in order to adapt the swage to act with equal efficiency upon different teeth, or, in other words, to accommodate the swage to such irregularities or variations in the teeth as are produced by filing and gumming; third, in the provision of a reversible supporting-die, having a convex or oval face capable of drawing out the point of the tooth endways or spreading the same sideways; fourth, in the provision of a spring-holder for the stamping or striking-die, the latter being thereby constantly held to its work.

Figure 1 is a perspective view of a swage illustrating my invention.

Figure 2 embraces two views of the dies, the lines of vision of the different views being at right angles to each other.

Figure 3 is a perspective view of a modified form of my improved swage.

Similar letters of reference indicate corresponding parts in the different figures.

In the drawings, A represents a swage-stock, and B the die or pin upon which rests the cutting-point of the saw-tooth when under the action of the stamping or striking-die C. The saw-tooth (which is indicated in red lines in fig. 1) is set between the pins D D and E E, whereby it is held against lateral displacement when acted upon by the striking-die C. If preferred, the saw-tooth may be held against lateral movement by being set in suitable grooves in the swage-stock, instead of between the pins. The socket or aperture in the swage-stock in which the swage-pin or die B is placed, communicates with the rectangular opening F, which receives a wedge, G, which serves to support said swage-pin. The position of the wedge G is regulated by means of a set-screw, H, so as to raise or lower the swage-pin and support the same in the required position to sustain the point of the saw-tooth. This adjustment of the swage-pin in relation to the front of the stock A, which serves as a bearing for the shank of the tooth under treatment, enables the swage to be applied with equal effect to different teeth, and to accommodate itself to such irregularities as are produced by filing and gumming. If desired, a stationary die, B, may be employed, and the edge of the saw-tooth supported by a wedge, G, adjustable by a set-screw, H, within a dove-tailed opening, as shown in fig. 3. It will be observed that in the device shown in fig. 3 the bearing-point (or wedge) for the shank of the saw-tooth is adjusted or changed in relation to the die B upon which the point of the tooth is hammered or swaged, whereas with the device shown in fig. 1 the same object is attained by the adjustment of the die or swage-pin B in relation to the bearing-point on the stock. In either case, the adaptation of the swage to different teeth, and to variations therein, supplies a very important desideratum, and enables the instrument to be more extensively and efficiently brought into requisition. The front of the swage-stock A is notched, as at a, and these notches are designed to engage with corresponding serrations on the shank of the saw-tooth, as shown, to prevent the tooth from springing back, and thus retain its point upon the supporting-die B when subjected to the blows of the hammer applied to the stamping-die C. The notches a may either extend entirely across the front or face of the stock A, or be merely long enough to receive the serrations on the saw-tooth. The supporting-die B, fig. 1, has an oval or convex face, b, as shown clearly in fig. 2, so that when it is in the position shown in fig. 1, it has the effect to spread the point of the tooth sideways when acted upon by C. By reversing the position of the die, (i. e., by withdrawing the same, turning it one-quarter round and re-inserting it,) it has the effect to draw out the point of the tooth endwise. The die B is held against turning, when in either position, by its square shank, which projects downward into the opening F. The striking-die C is mounted in a spring-holder, C¹, adjustably attached to the stock by means of a set-screw, C², and serving to keep the die down to its work. The die C spreads the tooth some distance back from its cutting-edge, and thus causes it to make smoother work in sawing.

Having thus described my invention, what I claim herein as new, and desire to secure by Letters Patent, is—

1. The provision of notches or teeth, α , on the swage-stock, to hold the notched or serrated saw-tooth against displacement, substantially as described.
2. The adjustable swage-pin or die B, or its described equivalent, whereby the swage is made to accommodate or adapt itself to irregularities or variations in the saw-teeth, substantially as described.
3. A reversible supporting-die or swage-pin, B, having a convex or oval face, in order to either spread the tooth sideways or draw the same endways, substantially as described.
4. The die or stamping-device C, in combination with the spring-holder C¹ and adjusting-screw C², substantially as and for the purpose set forth.

To the above specification of my new and useful improvement in swages for saw-teeth, I have signed my hand, this 15th day of July, A. D. 1867.

NELSON JOHNSON.
